CLAIM

The ornamental design for a pickleball sling, as shown and described.

DESCRIPTION

FIG. 1 is a front perspective view of the pickleball sling claimed herein;

FIG. 2 is a front elevation view thereof;

FIG. 3 is a rear elevation view thereof;

FIG. 4 is a side elevation view thereof;

FIG. 5 is a side elevation view thereof;

FIG. 6 is a top plan view thereof;

FIG. 7 is a bottom plan view thereof; and,

FIG. 8 is a rear perspective view thereof.

The wide dash broken lines are to show portions of the pickleball sling and form no part of the claimed design. The short dash broken lines are to show stitching and form no part of the claims design.

1 Claim, 7 Drawing Sheets
